UNITED STATES PATENT OFFICE.

JEAN BAPTISTE DÉSIRÉ MAXIMILIEN MALEZIEUX, OF PARIS, FRANCE.

CARBURETER FOR EXPLOSIVE-ENGINES.

No. 823,608.

Specification of Letters Patent.

Patented June 19, 1908.

Application filed July 18, 1904. Serial No. 217,069.

To all whom it may concern:

Be it known that I, JEAN BAPTISTE DÉSIRÉ MAXIMILIEN MALEZIEUX, a citizen of the Republic of France, and a resident of Paris, France, have invented a new and useful Carbureter for Explosive-Engines, which is fully set forth in the following specification.

This invention relates to a carbureter in which the atomizing of the liquid carbureting medium is obtained by means of a current of air passing across the end of the sheet or jet injector, thereby drawing the hydrocarbon to the ends of the ejector tubes or slots arranged for the purpose and immersed in the liquid, the air-current being produced by any suitable means, more particularly by means of the vacuum produced by the engine when working.

In order to render the description as clear as possible, several constructions of the carbureter according to this invention are illustrated, by way of example, in the accompanying drawings.

Figure 1 is an elevation, and Fig. 2 is a perspective view, of a carbureter in vertical section, certain parts being removed to show the construction of the sheet-jet. Figs. 3 to 6 show details of spring-valves admitting air to the carbureter in question.

The carbureter, Fig. 1, is designed so that a multiplicity of jets are replaced by a jet in the shape of a sheet, so as to render the atomizing continuous, the object of this being always to have the same proportion of hydrocarbon whatever be the opening of the passage admitting the explosive-gas mixture to the engine-cylinder. This is, as a rule, very difficult to attain with multiple jets. Secondly, the valve controlling the supply of air to be mixed with the atomized hydrocarbon and which is liable to quick wear is replaced in this construction by a flat spiral or conical or helical spring acting as a valve. Moreover, this construction of carbureter is combined with a pneumatic governor.

The arrangement of the jet in the shape of a sheet necessitates, chiefly, two longitudinal substantially parallel grooves *a b*, Fig. 2, and a flattened tube *c* of the same width as the grooves *a b*. This tube plunges into the hydrocarbon in the reservoir *d* of the carbureter. Air enters freely through the groove *a* and causes the flow of the hydrocarbon, which rises through the tube *c* to the orifice of the slot *b*. On escaping from the

slot *b* the hydrocarbon is literally pulverized by the air.

Referring to Figs. 1 and 2, *n* is an air-receiving chamber provided with a valve *i*, through which air is permitted to enter when the pressure within the chamber is reduced below that of the atmosphere. *g'* is a carbureted air-delivery chamber which communicates with chamber *n* through an opening *f* and which is connected at *g'* by a conduit *s*, Fig. 1, with a suitable pressure-reducing device, such as an explosive-engine. For the purpose of regulating the size of the communicating opening *f* between the chamber *g'* and *n* two sliding valves *g* and *e* are provided. The valve *g* is raised and lowered by any suitable means, such as a screw 38. Valve *e* is actuated by fluctuations of pressure in the suction-pipe *s* between the engine, for example, and the carbureter, and for this purpose valve *e* is connected by a lug 39 to a rod *t* with a piston *q* in cylinder *p*, communicating at *r* with conduit *s*. For the purpose of simultaneously controlling the delivery of oil-spray to the air passing through opening *f*, slide-valve *e* is made L-shaped, the horizontal member having a slot which extends nearly across the width of the member and divides it into two portions *e' e''*, which latter rest over the grooves or passages *a* and *b*. Depending from the bottom wall of chamber *n* is a flange 40, entering the groove between portions *e' e''* and forming a closure for the chamber at this point. It will thus be seen that any movement of the piston *q* will be transmitted through rod *t* to valve *e* and its horizontal members *e' e''*, and thereby slide over the openings *f*, *b*, and *a* to regulate the air entering groove *a*, the oil-spray passing out of *b* and the quantity of air passing through opening *f*. A regulating-register *g*, capable of moving vertically, and the slide-door *e*, co-operating therewith, determine at *f* the opening required for the supply of hydrocarbon.

The valve *i*, shown on the right-hand side of the carbureter, Fig. 2, can be advantageously replaced either by a spiral spring *h* of flat shape, Fig. 3, or by a conical spiral spring *i*, Figs. 4 and 5, or by a helical spring *j*, closed at one end by means of a disk or washer *k*, Fig. 6. The springs in question can be rendered adjustable by combining, in the manner illustrated in Figs. 3, 5, and 6, a spring *l* acting in opposition and compressed by means of a nut *m*. These spring-

valves wear almost indefinitely, they are perfectly silent, and their working is very elastic.

The carbureter having been assembled and the three supplies through *a*, *b*, and *f* having been judiciously combined, the register *g* properly adjusted, as well as the tension of the spring-valve *h*, *i*, or *j* arranged at *n* on the carbureter, no variation in the carbureting of the air can take place whatever be the speed of the engine.

The pneumatic governor consists of a cylinder *p*, Fig. 1, provided with a piston *q*, and operates the slide *e* by the action of a vacuum. The cylinder *p* communicates directly at *r* with the suction-pipe *s* between the engine and the carbureter. The piston *q* is secured to the rod *t* of the slide *e*, the other end of the rod *t* passing through a spring *u*, acting in opposition to the piston *q*. The tension of the said spring resting against the part *u'* can be adjusted by means of a nut *v*, screwed on the screw-threaded end of the rod *t*. The face of the piston away from the engine is exposed to atmospheric pressure.

Every time that the vacuum produced by the suction of the engine is sufficiently strong to overcome the resistance of the spring *u* the piston *q* is drawn toward the left, Fig. 1, carrying with it, consequently, the slide *e*, which closes at the same time the passage-openings for hydrocarbon and air. If the spring *u* be adjusted for a speed of *x* revolutions of the engine, each time that this number is slightly exceeded or even attained the piston *q*, acting as a governor, causes the engine to slacken down until the vacuum becomes normal. It is therefore possible, first, to produce variable quantities of carbureted air without possibility of changes in the charging owing to the mere fact that it is impossible to uncover a jet without simultaneously giving passage to such a quantity of air that its output can be properly carbureted; second, to vary the power of the engine and to maintain it working at any intermediate point between the maximum and the minimum without fear of any trouble with the carbureting; third, to effect a considerable economy in the consumption of hydrocarbon owing to the uniformity of the charging,

and, fourth, to effect the carbureting so that the combustion of the mixture is perfect and there is an absence of smell at the exhaust.

I claim—

1. In a carbureter, the combination of a reservoir, for containing a carbureting liquid, an air-receiving chamber having an air-inlet, a valve normally closing said inlet, a carbureted air-delivery chamber communicating with said air-chamber, a spraying device delivering said liquid to the air-chamber, a valve simultaneously controlling said spray device and a passage between said two chambers, and a valve for independently controlling said passage. 65

2. In a carbureter, the combination of a reservoir for containing a carbureting liquid, an air-chamber having an air-inlet, a valve normally closing said inlet, a carbureted air-delivery chamber communicating with said air-chamber, a spraying device, comprising a flattened tube having one end opening into the reservoir and the other provided with branching conduits, one communicating with the atmosphere and the other with the air-chamber, and a valve simultaneously controlling the passage between said chambers and the openings of said slits. 75

3. In a carbureter, the combination of a reservoir for containing a carbureting liquid, 80 an air-chamber having an air-inlet, a valve normally closing said inlet, a carbureted air-delivery chamber communicating with said air-chamber, a spraying device comprising a flattened tube having one end opening into 85 the reservoir, and the other provided with branching conduits, one communicating with the atmosphere and the other with the said air-chamber, and an L-shaped valve simultaneously controlling the passage between said chambers and the openings of said branching conduits. 90

In testimony whereof I have signed this specification in the presence of two subscribing witnesses.
